Attorney

UNITED STATES PATENT OFFICE.

OTTO SCHAUMBERG, OF PITTSBURGH, PENNSYLVANIA.

HAIR-WAVING APPARATUS.

Application filed December 5, 1921. Serial No. 520,092.

To all whom it may concern:

Be it known that I, Otto Schaumberg, a citizen of the United States, residing at Pittsburgh, in the county of Allegheny and

State of Pennsylvania, have invented certain new and useful Improvements in Hair-Waving Apparatus, of which the following is a specification.

This invention relates to an electrically heated hair waving apparatus, and has for its object to provide, in a manner as herein-after set forth, a simple and durable hair waver by the use of which inexperienced persons can readily and expeditiously give to their hair a smooth wave-like shape, which is far more desirable than what can be accomplished by the use of the ordinary type of curling irons, which latter require the distortion of the hair, by pushing and twisting, under such conditions causing damage to the hair.

Briefly described the invention has special reference to an electric heating element located in a corrugated base, and a fork consisting of two prongs, these latter providing the means for pressing the hair against the walls of the corrugated base, which base is constantly heated by the electric heating element.

To the accomplishment of the above mentioned objects and such other objects as may hereinafter appear, the invention consists of the novel construction, combination, and arrangement of parts herein specifically described, and illustrated in the accompanying drawing wherein is shown an embodiment of the invention, but it is to be understood that changes, variations, and modifications may be resorted to which come within the scope of the claims hereunto appended.

In the drawing forming a portion of this specification and wherein like numerals of reference designate corresponding parts throughout the several views:—

Figure 1 is a side view of an electric hair waving apparatus in accordance with the invention and with portions thereof shown in cross section.

Figures 2 and 3 are respectively top and bottom plan views of the device.

Figure 4 is a sectional view on line IV—IV, Figure 1.

Figure 5 is a fragmentary detail view of the core of the heating element.

Referring in detail to the drawing 1 denotes a corrugated base or body portion of

W-shape and which is formed to provide a pair of longitudinal and parallelly extending inverted V-shaped grooves 2 on the outer face of the base, and a longitudinal V-shaped groove 4 centrally disposed on the inner face of the base. A suitable metal cover 5 engages the side walls of the base 1, as clearly shown in Figure 4, and in conjunction with the base 1 forms a completely enclosed chamber 6. The assembly of the cover 5 with the base 1 may be made permanent or detachable as desired.

The electric heating element 7 is mounted to extend in the groove 4 of the base, and comprises a core 8 of refractory material upon which the resistance heating coil 9 is wound. The core 8 is connected to and rigidly supported in position by the terminal block 10, which latter is fixedly clamped, as at 11, upon the rear end of the base 1 upon its assembly with the cover 5. The terminals 12 of the coil 9 extend through insulated apertures 13 in the terminal block 10 and connect with the feed wires 14 adapted to transmit the electrical energy.

The entire inner wall of the chamber 6 is covered with suitable insulating materials 15. The arrangement of the latter and the position of the coil 9 will permit of the base 1 intensely heating while the coil 9 is functioning, and prevent and retard the transmission of the heat to the cover 5.

A metallic fork consisting of two forwardly projecting tines or prongs 16 is pivotally connected, as at 17, by its shank 18, to the shank 19, which latter extends along in and is fixedly secured to the bottom of the groove 4 of the base 1. The shanks 18 and 19 are respectively provided with handles 20 and 21, at their rear ends. The prongs 16 are curved longitudinally.

The pivotal connection of the shank 18 with the shank 19 is such that when the handles 20 and 21 are drawn toward each other by the hand of the operator, a prong 16 of the fork will be positioned to provide a pressure action towards and against the bottom of each of the grooves 2 of the base 1. When the handles 20 and 21 are moved away from each other the prongs 16 will entirely clear the base 1. In other words, the pivotal connection 17 permits of a scissor like motion shifting the prongs 16 into and out of engagement with respective grooves 2 formed in the base 1.

The base 1 and associated parts are

- curved longitudinally, as at 22, to conform, as nearly as possible, to the mean curvature of the contour of the human head against which the device is adapted to operate. The lower edges of the side walls of the base 1 are flared outwardly, as at 23, to eliminate possibility of offensive sensations concomitant in the use of the apparatus when in contact with the head.
- 10 In practice the base 1 is heated for a brief period by energizing the coil 9 before applying the device to the hair. The fork member, in the open position, may be readily inserted in the hair, and by drawing handles 20 and 21 together the hair on the fork member will be engaged and forced into the grooves 2 of the now heated base 1 and held under pressure for a short time, thereby forming a lasting wave-like shape 15 to the hair thus engaged, conforming to the contour of the corrugated base.

What I claim is—

1. An electric hair waving apparatus comprising a base formed with an inner V-shaped corrugation and a pair of outer corrugations disposed in parallelism and each of inverted V-shape, a heating element supported at one end from one end of the base and extending lengthwise of the inner corrugation, and a fork element shiftable into and out of the outer corrugations of the base.
2. An electric hair waving apparatus comprising a base formed with a V-shaped inner and a pair of inverted V-shaped outer corrugations, a heating element mounted within the inner corrugation, a fork element shiftable into and out of the outer corrugations of the base, and a cover enclosing the outer walls of the outer corrugations and enclosing the heating element.
3. An electrical hair waving apparatus comprising a W-shaped base curved longitudinally, said base formed with a pair of longitudinal parallel grooves on its outer face and with a longitudinal groove on its inner face disposed centrally with respect to the said pair of grooves, a terminal block positioned at the rear end of the base and supporting a heating element at one end of the latter, said heating element extending lengthwise of said groove on the inner face of the base, a cover mounted on the base enclosing the heating element and adapted for clamping said terminal block on said base, a fork element including a pair of prongs, said fork shiftable to position one of said pair of prongs into and out of each of said pair of outer grooves, said pair of prongs being curved longitudinally.
4. An electrical hair waving apparatus comprising a W-shaped corrugated base arcuate in the direction of its length, a pair of pivotally connected elements, one of said

elements including a tine arcuate in the direction of its length and secured in one of the corrugations of the base, the other of said elements including a pair of tines adapted to be shifted into the other corrugations of the base and co-operating with the walls thereof and each arcuate in the direction of its length, and an electric heating element secured at one end with one end of the base and extending lengthwise of the corrugations in which a tine is secured.

5. An electrical hair waving apparatus comprising a W-shaped corrugated base arcuate in the direction of its length, a pair of pivotally connected elements, one of said elements including a tine arcuate in the direction of its length and secured in one of the corrugations of the base, the other of said elements including a tine arcuate in the direction of its length and secured in one of the corrugations of the base, the other of said elements including a pair of tines adapted to be shifted into the other corrugations of the base and co-operating with the walls thereof and each arcuate in the direction of its length, and an electric heating element secured at one end with one end of the base and extending lengthwise of the corrugations in which a tine is secured, and a cover enclosing that corrugation provided with the heating element and engaging the outer walls of the other corrugations.

6. An electrical hair waving apparatus comprising a W-shaped corrugated base arcuate in the direction of its length, a pair of pivotally connected elements, one of said elements including a tine arcuate in the direction of its length and secured in one of the corrugations of the base, the other of said elements including a pair of tines adapted to be shifted into the other corrugations of the base and co-operating with the walls thereof and each arcuate in the direction of its length, and an electric heating element secured at one end with one end of the base and extending lengthwise of the corrugations in which a tine is secured, the outer walls of those corrugations into which said pair of tines is shifted into having the free termini thereof angularly disposed outwardly with respect to the remaining portion of said walls.

7. An electrical hair waving apparatus comprising a W-shaped corrugated base arcuate in the direction of its length, a pair of pivotally connected elements, one of said elements including a tine arcuate in the direction of its length and secured in one of the corrugations of the base, the other of said elements including a tine arcuate in the direction of its length and secured in one of the corrugations of the base, the other of said elements including a pair of tines adapted to be shifted into the other corrugations

gations of the base and co-operating with the walls thereof and each arcuate in the direction of its length, and an electric heating element secured at one end with one end of the base and extending lengthwise of the corrugations in which a tine is secured, and a cover enclosing that corrugation provided with the heating element and engaging the outer walls of the outer corrugations, and said elements further including oppositely disposed handles offset with respect to the pivot between said members.

8. An electrical hair waving apparatus comprising a base formed with an inner and a pair of outer corrugations arranged in parallelism, a pair of fork elements pivotally connected together intermediate the ends thereof and each having its rear portion constituting a handle, the forward portion of one of said elements providing a tine extending in said inner groove and connected to the base, the forward portion of the other of said elements providing a pair of tines adapted to be shifted into and out of the outer corrugations, and an electric heating element having one end secured with one end of the base and extending

lengthwise of said inner corrugation above the tine therein.

9. An electrical hair waving apparatus comprising a base formed with an inner and a pair of outer corrugations arranged in parallelism, a pair of fork elements pivotally connected together intermediate the ends thereof and each having its rear portion constituting a handle, the forward portion of one of said elements providing a tine extending in said inner groove and connected to the base, the forward portion of the other of said elements providing a pair of tines adapted to be shifted into and out of the outer corrugations, and an electric heating element having one end secured with one end of the base and extending lengthwise of said inner corrugations above the tine therein, and a cover enclosing said heating element and inner corrugation and having its sides frictionally engaging the outer walls of said outer corrugations whereby the cover is secured to the base.

In testimony whereof I affix my signature.

OTTO SCHAUMBERG.
